(57) **CLAIM**

The ornamental design for a footwear, as shown and described.

DESCRIPTION

FIG. 1 is an isometric view of a footwear.

FIG. 2 is a front elevation view of the footwear of FIG. 1.

FIG. 3 is a rear elevation view of the footwear of FIG. 1.

FIG. 4 is a left side elevation view of the footwear of FIG. 1.

FIG. 5 is a right side elevation view of the footwear of FIG. 1.

FIG. 6 is a top plan view of the footwear of FIG. 1; and, FIG. 7 is a bottom plan view of the footwear of FIG. 1.

The heavy dashed lines in FIGS. 1-7 show stitching and form a part of the claimed design. The short dashed lines in FIGS. 1-7 show features that do not form a part of the claimed design.

1 Claim, 6 Drawing Sheets
